APPLICATOR

Robert H. Van Sant, Alexandria, Va.

Application August 20, 1945, Serial No. 611,475

14 Claims. (Cl. 128—272)

1

This invention relates to applicators for medicinal and similar liquids, having for its object to provide a completely sealed unit package containing a specified quantity of such liquid, and adapted by its construction to provide a ready and efficient means for applying the specified quantity as a dosage to the parts of the human body to be treated.

With these and other objects in view, which will become apparent as the following description and drawings are studied, the invention resides in the novel details of construction and combinations of parts as will be disclosed more fully hereinafter and particularly pointed out by the claims.

Referring to the accompanying drawings, forming a part of this specification and in which like numerals designate like parts in all the views—

Figs. 1, 2, 3, 4 and 5 illustrate diagrammatically transverse horizontal sectional views of contemplated forms of containers constituting the applicator of this invention;

Figs. 6, 7, 8 and 9 illustrate diagrammatically vertical sectional views of the lower portions of contemplated forms of containers;

Figs. 10, 11, 12 and 13 illustrate diagrammatically vertical sectional views of the upper portions of contemplated forms of containers; and

Figs. 14 and 15 illustrate diagrammatically vertical sectional views of two major types of applicator teats adapted to pass the liquid from the container to the human body.

The container may be made of any suitable material or substance, although preferably it is formed from mouldable substances which can be cast readily while in their fluid phase, and hence plastics and/or gelatines are desirable as not only fulfilling such characteristics but providing reasonably stiff, unyielding and/or readily manipulable containers when fully moulded, cured, dried and cooled, etc. The substance may also be selected according to its ability to effect a seal for the container during or at the end of the moulding operation, yet on the other hand and for certain medicaments it may be desirable to select a substance which will permit the moulding of a completely closed container which may be filled later and sealed through the instrumentality of a plug. Such a sealed container as contemplated by this invention will insure maximum quality of the liquid contents, since there will be no loss by evaporation, nor deterioration, nor contamination. Methods are already known by which such a container may be moulded and filled on the same machine.

The liquid contents of the container or appli-

cator will be, naturally, in accordance with the use for which the applicator is intended but, generally speaking, the liquid will be some medicament, tonic, oil, etc., particularly beneficial in its external application, as through massaging, to the human body. Quite specifically, it may be a tonic for the hair and general treatment of the scalp.

The liquid may be of variable viscosity, and the mechanics of effecting a flow thereof either naturally, or by air pressure, are governed by the viscosity. The size of the container also will be variable, though for practical and economic reasons it will be found desirable to form the container in sizes for single applications and hence the size will be determined preferably in accordance with the dosage or quantity best suited for a single application of the particular liquid or fluid without waste. As one example, it will be found that an applicator capable of containing a liquid volume of 5 cc., and comprising multiple discharge nipples or teats, will be of a size which can be held easily in the fingers and which will afford ready spread of the liquid onto and over the body surface being treated.

With particular reference to the drawings, various possible shapes of containers are indicated, wherefore it will be appreciated that the invention is not limited to any particular form, shape or size, and that numerous modifications may be formed by appropriate and desirable combinations of top portions and bottom portions. According to Figs. 1 and 2 the container may be relatively unicellular, whereas according to Figs. 3, 4 and 5 it may be relatively multicellular. In fact, the container may be substantially spheroidal or tubular, and its cross-sectional shape may be circular or polygonal, or a combination thereof, and a unicellular container may have such a cross-sectional shape as will permit it to coif with one or more similarly and/or complementally shaped containers within a single holder or package in order to produce an assembled group of independent cells (containing the same or different medicaments) instead of the intercommunicating cells as shown in Figs. 3, 4 and 5. In Figs. 6 and 9 are indicated relatively blunt, rounded, smooth discharge teats particularly adapted for massaging and/or treating tender skins, whereas in Figs. 7 and 8 are indicated teats of more angular and sharper characteristics, the latter particularly adapted to reach closer to the base of hairs as when the applicator is for use in scalp treatments.

In the drawings, the sectional shapes and/or

formations are illustrated diagrammatically, the heavy line such as 2 indicating the cut edge or actual cross-section of the container wall, and the thin line such as 3 indicating the elevational meeting edge of adjoining wall surfaces. The small circles 4 shown within the confines of the containers of Figs. 4 and 5 represent special teat-like formations at the extreme bottom of each cell of the container, which formations may be the same as or similar to those shown in Figs. 14 and 15 and which are adapted to facilitate the sundering of the container, by severing, puncturing or other method of opening, in order to permit discharge of the contained liquid.

That is to say the formation shown in Fig. 14 lends itself to the puncturing method, while the outwardly projecting tip or nipple shown in Fig. 15 may be cut off readily, either entirely or partially, to provide a larger discharge opening as in the case where the applicator contains a relatively thicker liquid. It is to be understood that the puncturing method provides a small opening for discharging the liquid in relatively small quantities and/or at slow rates. However, it is further to be understood that with either method of container opening, there is capillary attraction and/or adherence of the liquid to the body surface, which results in a "pulling" effect imparted to the liquid which aids in the extraction (or discharge) of the liquid from the container while in contact with the body surface during the use of this applicator, which extraction is augmented as and when the body surface is wet as in the case of scalp treatment after shampooing.

It is a feature of this invention to provide positive means for applying the medicament to the body surface in such manner as will give greatest benefit. This is attained by permitting relatively small quantities of the liquid to escape, whereby the medicament is controlled so as to cover the maximum surface and is not "dumped" in spots as is apt to be the case with containers having collapsible or flexible walls which are subject to pressure by the fingers. This control of the medicament flow may be augmented and/or rendered more positive by the employment of an air vent capable of being formed in the top of the container. That is to say, in Figs. 10, 11 and 13 there are indicated top portions of the container which are adapted to be punctured, whereas in Fig. 12 there is shown a projecting nipple 6 which is to be cut off in order to provide the air vent. In Fig. 11 there may be provided an inwardly directed wall recess 5 in the top portion of the container, for facilitating entry of the puncturing implement.

In lieu of providing a potential positive air vent in the top portion of the container, one of the teats at the bottom portion may be made slightly shorter than the others as indicated at 7 in Fig. 8, whereby in the use of the applicator the short teat ordinarily will not contact the body surface. Hence there will be, at least at times, an air gap at the cut discharge opening of the short teat, permitting ingress of air through that teat into the container.

It is obvious that those skilled in the art may vary the details of construction and arrangements of parts without departing from the spirit of this invention, and therefore it is desired not to be limited to the exact disclosure of this application, except as may be required by the claims.

What is claimed is:

1. An applicator comprising a rigid cellular structure moulded with a liquid medicament sealed therein, said cellular structure provided with one sunderable portion constituting a discharge for the contained medicament and further provided with another sunderable portion constituting an air inlet.
2. An applicator comprising a unit package with sealed-in liquid medicament, said package having relatively rigid walls and provided at one end with projections which when severed constitute discharges for the contained medicament, said package provided at the opposite end with severable means for admitting air to the container.
3. An applicator comprising a unit package with sealed-in liquid medicament, said package provided at one end with projections which when severed constitute discharges for the contained medicament, and another projection shorter than the others which when severed constitutes an air inlet.
4. An applicator comprising a unit package with sealed-in liquid medicament, said package provided at one end with projections which when severed constitute discharges for the contained medicament, and an air vent disposed amid said projections.
5. An applicator for manipulation upon a body surface, said applicator comprising a rigid unit package with sealed-in medicament, said package provided at one end with an integrally formed teat-like projection having a tip portion which is sunderable to unseal said package, said tip portion being of relatively minute transverse dimension so that when sundered and applied to the body surface there is constituted a capillary discharge for the contained medicament, said package provided at the opposite end with an integrally formed seal as well as with another sunderable portion which when sundered constitutes an air inlet to the package.
6. An applicator comprising a plurality of rigid cell-like structures, said structures having an integrally formed seal whereby to seal a liquid medicament therein, each of said cell-like structures provided with a hollow projection adapted to contact a body surface during the use of the applicator, the tip of said projection having a sunderable portion of relatively minute transverse dimension which when sundered creates a discharge for the contained medicament under the influence of capillary attraction.
7. An applicator comprising a plurality of cell-like structures, said structures having an integrally formed seal whereby to seal a liquid medicament therein, at least one of said cell-like structures provided with a hollow projection adapted to contact a body surface during the use of the applicator, the tip of said projection being sunderable to create a discharge for the contained medicament through said hollow projection, said applicator provided with a sunderable portion which when sundered constitutes an air inlet to one of the cell-like structures.
8. An applicator comprising a plurality of cell-like structures having a liquid medicament sealed therein, said cell-like structures provided with hollow projections adapted to contact a body surface during the use of the applicator, the tip of each projection being sunderable to create a discharge for the contained medicament through said hollow projection, and a portion of at least

one of said cell-like structures being sunderable to provide an air inlet.

9. An applicator comprising a plurality of cell-like structures having a liquid medicament sealed therein, said cell-like structures provided with hollow projections adapted to contact a body surface during the use of the applicator, the tip of each projection being sunderable to create a discharge for the contained medicament through said hollow projection, and a portion of at least one of said cell-like structures being sunderable to provide an air inlet disposed amid said projections.

10. An applicator comprising a plurality of cell-like structures having a liquid medicament sealed therein, said cell-like structures provided with hollow projections adapted to contact a body surface during the use of the applicator, the tip of each projection being sunderable to create a discharge for the contained medicament through said hollow projection, and a portion of at least one of said cell-like structures being sunderable to provide an air inlet disposed substantially opposite one of said projections.

11. An applicator comprising a unit package with sealed-in liquid medicament, said package comprising a rigid and unyielding hollow body portion having an outlet projection at one end and forming an integral part thereof, the extremity of said projection having an integrally formed sealed discharge portion of relatively minute transverse dimension which when sundered permits escape of the contained medicament under the influence of capillary attraction, the opposite end of said body portion having an integrally formed seal.

12. An applicator comprising a moulded cellular structure of rigid and unyielding characteristics, said structure having an integrally formed seal whereby to seal a liquid medicament therein, said cellular structure provided at one end with an integrally formed projection having a relatively minute transverse discharge area which

when sundered permits escape of the contained medicament under the influence of capillary attraction.

13. An applicator for manipulation upon a body surface, said applicator comprising a rigid unit package with sealed-in medicament, said package provided at one end with an integrally formed teat-like projection having a tip portion which is sunderable to unseal said package, the opposite end of said package having an integrally formed seal, said tip portion having a relatively minute transverse dimension so that when sundered and applied to the body surface there is constituted a capillary discharge for the contained medicament.

14. An applicator for manipulation upon a body surface, said applicator comprising a rigid unit package with sealed-in medicament, said package provided at one end with an integrally formed teat-like projection having a tip portion which is sunderable to unseal said package, the opposite end of said package having an integrally formed seal, said tip portion having a relatively minute transverse dimension so that when sundered and applied to the body surface there is constituted a capillary discharge for the contained medicament, said package further provided with another sunderable portion which when sundered constitutes means for admitting air to the package.
